PORTABLE GARMENT RACK

Mary A. Toombs, 480½ N. Olive,
Orange, Calif. 92666

Filed Mar. 3, 1967, Ser. No. 6,049

Term of patent 14 years

(Cl. D33—3)

FIG. 1 is a perspective view illustrating the top and one side of a portable garment rack embodying the design of this invention including dotted lines showing garment hangers for illustrative purposes only; and

FIG. 2 is an elevation view of one side thereof, the rack being symmetrical.

The design is characterized by the clover-leaf knob and paired perforated cross members in combination with the vertical telescoping column and stepped circular base, all as shown.

I claim:

The ornamental design for a portable garment rack, as shown and described.
